UNITED STATES PATENT OFFICE.

WILLIAM D. GHARKY, OF PHILADELPHIA, PENNSYLVANIA, ASSIGNOR TO
THE SUN ELECTRIC MANUFACTURING COMPANY, OF NEW YORK.

DESIGN FOR A TELEPHONE SWITCH-BOX.

SPECIFICATION forming part of Design No. 32,616, dated May 1, 1900.

Application filed February 17, 1899. Serial No. 705,906. Term of patent 14 years.

To all whom it may concern:

Be it known that I, WILLIAM D. GHARKY, a citizen of the United States, residing at Philadelphia, county of Philadelphia, and State of Pennsylvania, have invented and produced a new and original Design for a Telephone Switch-Box, of which the following is a specification, reference being had to the accompanying drawings, forming a part hereof.

10 Figure 1 is a front view of a telephone switch-box, showing my new design. Fig. 2 is a side view, and Fig. 3 is a back view, thereof.

As shown in the drawings, the leading or material feature of my design consists of the 15 cylindrically-shaped box A, having plane or

flat ends a a'. The surface of the cylinder is plain and the face a' is transparent, thus giving to the whole a lighter and more graceful appearance and allowing a view of the interior.

Having described my invention, what I claim as new, and desire to secure by Letters Patent, is—

The design for a telephone switch-box as herein shown and described.

WILLIAM D. GHARKY.
